CLAIM

The ornamental design for a automobile side panel set as shown and described.

DESCRIPTION

FIG. 1 is a front perspective view of the automobile side panel set showing my design;

FIG. 2 is a rear perspective view thereof;

FIG. 3 is a front elevation view thereof;

FIG. 4 is a right-side view thereof;

FIG. 5 is a rear elevation view thereof;

FIG. 6 is a top plan view thereof; and,

FIG. 7 is a bottom view thereof.

Portions of the automobile side panel set and surrounding portions of an automobile shown in broken lines form no part of the claimed design.
